UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

WATER-TUBE BOILER.

1,044,660.

Specification of Letters Patent.

Patented Nov. 19, 1912.

Application filed April 6, 1912. Serial No. 688,828.

To all whom it may concern:

Be it known that I, DAVID S. JACOBUS, a citizen of the United States, residing at Jersey City, in the county of Hudson and State of New Jersey, have invented certain new and useful Improvements in Water-Tube Boilers, of which the following is a specification.

The object of this invention is to prevent disturbance in circulation of a water tube boiler having at some distance below the bottom tubes of the boiler an extra series of tubes connected into the boiler circulation, and will be understood by reference to the accompanying drawings in which—

Figure 1 is a central longitudinal section through a boiler embodying the invention; and Fig. 2 a detail vertical section on the plane of the line 2—2 of Fig. 1, and Figs. 3 and 4, detail views of certain parts.

Similar reference numerals indicate similar parts of the several views.

For the purpose of illustrating the application of my invention I have selected a well-known type of boiler comprising a bank 1 of inclined tubes connected to front and rear headers 2 and 3 respectively. This bank of tubes is divided by transverse baffles to provide passes for the gases from the furnace 4 to the uptake, as is usual in that type of boiler. This type of boiler comprises a row of tubes 5 below and somewhat detached from the bank of tubes, said lower tubes being connected with the boiler circulation by expanding their ends into horizontal boxes 6 and 7 approximately rectangular in cross-section; said boxes being connected by short tubes or nipples 8 to the headers. If all of the tubes 5 should discharge their circulatory water into a single chamber it is possible that the circulation of the boiler might be disturbed by greatly varying heat conditions on opposite sides of the furnace. In order to prevent such disturbance of boiler circulation, diaphragms 9 are placed in either or both of the boxes 6 and 7, dividing the box into a number of separate chambers 10 thereby preventing the crossing over of the circulatory water from one end of the box to the other. The boxes may be divided by any desired number of diaphragms, five

being shown for the purpose of illustration, dividing the tubes of the bank into groups of two and three tubes in width. One or more of the tubes 5 communicate with the chambers 10, as shown in Fig. 2, and the diaphragms 9 may be so disposed as to provide one or more outlets from the box 6 connected to the front header 2, the water in each chamber of the box 6 being compelled to take its exit through the connecting tube or tubes in that particular portion of it into which it is supplied.

By the use of the diaphragms the circulation of the boiler is divided into vertical sections, that is to say two or three of the vertical headers, as the case may be, together with their heating tubes circulate independently of the remaining tubes of the boiler.

The special form of diaphragm employed by me as shown in Figs. 3 and 4 comprises a plate to which is secured a spring plate 11 by means of a bolt and nut 12. The diaphragms are inserted through suitable hand holes in the boxes and by tightening up the nut 12 the spring plate 11 is forced against the walls of the box.

The diaphragms need not make a perfectly tight fit, in fact, by allowing a small clearance an advantage is derived through the ability to drain out all water from the boxes in emptying the boiler without employing a large number of drainage pipes.

What I claim and desire to secure by Letters Patent of the United States is:—

A water tube boiler having a bank of inclined tubes, front and rear headers into which said tubes are expanded, a row of tubes below said bank, boxes into which said lower tubes are expanded, nipples connecting said boxes and headers, diaphragms dividing said boxes into a plurality of chambers, each chamber having one or more inlet holes and one or more outlet holes for connecting into the boiler circulation.

In testimony whereof I have hereunto signed my name in the presence of two subscribing witnesses.

DAVID S. JACOBUS.
